Primary Examiner — Susan Moon Lee(74) *Attorney, Agent, or Firm* — Steven R. Fairchild(57) **CLAIM**

The ornamental design for a pet feeder reminder board, as shown and described.

DESCRIPTION

FIG. 1 is a perspective view of a pet feeder reminder board showing my new design; and,

FIG. 2 is a front elevation view thereof.

The elements depicted in broken line are for illustrative purposes only and form no part of the design claim.

1 Claim, 2 Drawing Sheets(56)
